CASEMENT WINDOW HINGE

John Brownlie, Freeport, and Ralph Gerstenzang, Brooklyn, N. Y., and Almon C. Blamey, Rutherford, N. J.; said Blamey assignor to said Brownlie and said Gerstenzang

Application August 14, 1947, Serial No. 768,580

1 Claim. (Cl. 16—135)

1

This invention relates generally to hinges and more particularly to those of the French sash or casement window type in which the axis of pivotal movement of the sash element is spaced a substantial distance from the principal planes of the sash element and frame.

In the pivotal mounting of casement type windows, it is desirable for a number of reasons that the axis of pivotal movement be spaced a substantial distance from the plane of the window frame. One of the principal advantages which flows from this construction lies in the fact that a space is provided when the sash element is in an opened position, as for example, one in which the sash element forms 90 degrees with respect to the window frame. This space permits cleaning both sides of the window pane (not shown) from the interior of the building.

With the increasing use of metal windows by the utilization of materials having a low corrosion factor (such as stainless steel, bronze or aluminum), an interfitting of the movable parts is obtained which affords sufficiently low leakage so that weather stripping or gasketing may be eliminated. The maintenance of proper opening and closing movements of the movable sash requires therefore hinges of sufficient strength and stability.

It is therefore among the principal objects of the present invention to provide hinge structure which may be manufactured entirely by stamping and forming with the elimination of casting or welding operations.

Another object herein lies in the provision of hinge structure of the class described which, while light in weight and utilizing a minimum of material, may have high strength and stability.

Another object of the invention lies in the provision of hinge structure wherein parts of the hinge are connected to other parts by virtue of, and through their connection with the sash element.

Another object herein lies in the provision of hinge pivot means offering controlled friction and weatherproof qualities.

A feature of the invention lies in the trim appearance presented by the completed device.

Another object herein lies in the provision of truss hinges which may be manufactured in large scale at low cost to have a consequent wide distribution and use.

These objects and other incidental ends and advantages will more fully appear in the progress of this disclosure and be pointed out in the appended claim.

2

In the drawings in which similar reference characters designate corresponding parts throughout the several views:

Fig. 1 is a fragmentary sectional view of a sash element, with a hinge showing an embodiment of the invention, mounted thereon.

Fig. 2 is a front elevational view of Fig. 1.

Fig. 3 is an enlarged view in perspective.

Fig. 4 is a fragmentary plan view of the structure shown in Fig. 2 with the hinge in an opened position thereof.

Fig. 5 is a developed plan view of a blank from which the hinge is formed.

Fig. 6 is an enlarged fragmentary vertical sectional view as seen from the plane 6—6 on Fig. 3.

As will be obvious to those skilled in the art to which the present invention relates, the present hinges may be made in left hand or right hand types, and although a right hand type has been chosen for illustration, a mere reversal of parts will produce a left hand type. Where a pair of sashes are swung about their outer edges, the right hand type shown may be mounted at the upper left hand edge of the left hand sash element, and correspondingly, a lower left hand hinge may be used at the upper right hand edge of the right sash element.

The hinge, generally indicated by reference character 10, comprises broadly a relatively stationary or first hinge element 11; a relatively movable or second hinge element 12; and pivotal interconnecting means 13. While the stationary element 11 is shown as being connected to the window frame element 14, and the movable element 12 is shown as being connected to the window sash element 15, in certain applications it may be desirable to reverse this arrangement.

The stationary hinge element 11 is of irregular configuration, best seen in Fig. 4, and includes an attaching shank 16, shoulders 17 and 18, a relatively inner side edge 19, a relatively outer side edge 20 and an end 21. The end 21 is provided with an orifice 22.

The shank 16 may be provided with a plurality of orifices 23 and said shank is preferably attached to the sill or lower member 24 by extending through an orifice 25, of corresponding size, in the portion 26. The shank 16 may be attached to the portion 27 by rivets 28 or screws (not shown).

The movable hinge element 12 includes a base member 30, a base member attaching flange 31, a truss member 32, a truss member attaching flange 33 and an end 34. The base member 30 adjacent the end 34 is provided with an orifice 35.

The movable hinge element 12 is preferably

fabricated by blanking from sheet stock, a blank indicated by reference character 50a, the external configuration of which is shown on Fig. 5. In the blank 50a, for the purpose of avoiding repetition, certain of the parts corresponding to the parts of the hinge element 12 are given the same reference characters with a suffix "a." By blanking the piece 50a and bending the same through substantially 90 degrees along each of the bends 40, 41 and 42, the hinge element 12 is quickly and economically produced. The edges 36 and 37 are disposed at an angle of 45 degrees with respect to the bends 41 and 42 so that in the completed hinge these edges contact each other and cause the truss member 32 to be disposed at right angles with respect to the base member 30. This prevents the truss member 32 from moving toward the base member 30 in a forward direction as viewed in Fig. 3.

The flange 31 is provided with a plurality of orifices 38 and 39 and the rivets 43 and 44 extend through these orifices to secure the attaching flange 31 to the window sash element 15. The flange 33 is provided with a plurality of orifices 45 and 46 and the rivets 47 and 48 extend through these orifices to secure the attaching flange 33 to the window sash element 15. This makes the portion 49 of the window sash element 15 a gusset for the flanges 31 and 33 and obviates the necessity of welding or other joint connecting means between the juxtaposed edges 36 and 37.

The means 13 is preferably in the form of a rivet having a pin portion 52, an upper head 53 and a spun over enlargement 54. The stationary element 11 is separated from the base member 30 by a middle bearing 55. The head 53 is spaced from the base member 30 by the upper bearing 56 and the hinge element 11 is spaced from the enlargement 54 by the lower bearing 57. The middle bearing 55 has a central orifice of substantially the same diameter as the orifices 22 and 35 and interposed between the borders of said orifices and the pin 52 is a bushing 58. The bearings 55, 56 and 57 and the bushing 58 are composed of a textile material impregnated with a synthetic resin preferably of the phenolic condensation type. The said bearings and bushing are relatively non-hygroscopic and act to insulate metal to metal contact between the elements 11 and 12 and the means 13. By placing the bearings 55-57 and the bushing 58 under substantially no compression at the time that the free terminal of the pin 52 is headed over at 54, a pivotal connection of low friction is provided so that the sash element 15 in an assembled window may be readily adjusted in angularity with respect to the frame 14 by any suitable

actuating devices (not shown) well known in the art.

It may thus be seen that there has been provided a novel and useful hinge structure which combines high strength and stability with low weight and manufacturing costs. The self lubricating qualities of the bearings 55-57 and the bushing 58 provide for long trouble-free and noiseless operation.

We wish it to be understood that we do not desire to be limited to the exact details of construction shown and described, for obvious modifications will occur to a person skilled in the art.

We claim:

A casement window hinge comprising a flat hinge element having an attaching portion for the securing of the element to the casement window frame, said flat hinge element adapted to extend outwardly from the frame when attached thereto, a second hinge element adapted to be secured to the adjustable casement window, said second hinge element having a base portion adapted to overlie the flat hinge element when the window is closed and having a laterally extending attaching flange adapted to engage the adjustable window, a portion extending laterally from another side of the base portion and serving as a truss therefor, said truss portion having a laterally extending attaching flange lying in a common plane with the attaching flange of the base portion and adapted to engage the adjustable window, said attaching flanges having respectively angle cut edges which engage each other and serve to reinforce one another on their plane of attachment with the adjustable window and hinge pin means pivotally securing together the flat hinge element and the base portion of the second hinge element.
